Application May 13, 1957, Serial No. 658,617

1 Claim. (Cl. 181—57)

The invention disclosed in this application relates to exhaust mufflers for internal combustion engines and is illustrated in an embodiment thereof shown in the drawing appended hereto.

In recent years internal combustion engines having increased output power characteristics have been developed for both automobiles and trucks. These developments have in some instances also resulted in higher exhaust temperatures and in increases in volume and changes in frequencies of exhaust noise. Concurrently with these technical changes, legal restrictions have been imposed on both the frequency and volume of noise which is allowable both on highways and in urban areas.

In order to reconcile these technical and legal factors it has become necessary to develop better and more effective muffling devices for use on automotive vehicles. Many devices have been proposed to reduce this increased automotive exhaust noise to satisfactory and legally acceptable levels, but all such devices so far developed have the undesirable collateral effect of imposing an objectionable degree of back pressure on the engine exhaust system which serves to waste engine power and to reduce the operating efficiency of the engine.

Objects

One of the objects of my invention is to provide an automotive muffler capable of more rapid dissipation of heat from exhaust gases.

A further object of my invention is the provision of a muffler which imposes relatively little back pressure on the engine.

A further object of my invention is to provide a muffler capable of more effective modulation of exhaust noises.

A further object of my invention is to provide an effective muffler of simplified construction which can be produced at relatively low cost.

Further objects and features of my invention will be apparent from the subjoined specifications and claim when considered together with the accompanying drawings.

Drawings

Fig. 1 is a view in section of a muffler constructed according to my invention;

Fig. 2 is a view in enlarged section taken along line 2—2 of Fig. 1;

Fig. 3 is a view in enlarged section taken along line 3—3 of Fig. 1;

Fig. 4 is a view in enlarged section taken along line 4—4; and

Fig. 5 is a view in enlarged section taken along line 5—5 of Fig. 4.

Detailed description

Referring now to the drawings, it may be seen that I have disclosed a cylindrical muffler having two end caps and four intermediate baffles, each successive baffle having characteristics as to the number and size of orifices which differ from those of adjacent baffles. It

2

may also be noted that each baffle is spaced from adjacent baffles or end caps at different linear distances depending upon the position of the baffle in the muffler and upon the size, number and characteristics of the orifices in the baffles and end caps.

Referring in detail to the drawings it is seen that I have shown in Fig. 1 a muffler 10 having a cylindrical body portion 11, oppositely disposed substantially hemispherical end caps 12 and 13, an inlet tube 14, an outlet tube 15, and intermediate baffles 16, 17, 18 and 19 secured to said muffler 10 in the manner and having the configuration which is described hereafter in detail.

Inlet tube 14 has an inside diameter slightly greater than the outside diameter of the exhaust pipe 20 leading either from the exhaust ports or from the exhaust manifold of the engine with which muffler 10 is to be used. Inlet end cap 12 is formed in my preferred embodiment having the substantially hemispherical configuration shown in Fig. 1, although it may also be formed having a circular plane configuration if desired. End cap 12 has a centrally disposed circular opening 21 having an inside diameter substantially equal to that of inlet tube 14. Inlet tube 14 is secured by suitable gas-tight and heat-conducting means to the outer convex surface of end cap 12 with one of its ends in register with opening 21.

Cylindrical body 11 is formed with any length and inside diameter necessary to accommodate the passage of the exhaust gas output of the exhaust pipe 20 of an engine with which the device is to be employed.

Inlet end cap 12 has an outside diameter substantially equal to the outside diameter of cylindrical body 11 and is secured in gas-tight and heat-conducting peripheral engagement with one end of body 11 so as to extend axially therefrom.

Outlet end cap 13 is formed with a convex configuration similar to that of cap 12 and has a centrally disposed circular opening 22 having a suitable diameter not less than the diameter of opening 21 of inlet cap 12. Outlet tube 15 has an inside diameter substantially equal to that of opening 22 and is secured in gas-tight and heat-conducting peripheral engagement with end cap 13 so as to be in register with opening 22 and to extend axially from the outer or convex surface of end cap 13.

Baffle 19 is formed of suitable heat conducting material with the general circular configuration shown in Figs. 4 and 5 with an outer annular flange 23 extending perpendicular to one face 24 of said baffle and having an outside diameter after forming substantially equal to the inside diameter of body 11. Baffle 19 is further formed with a centrally disposed orifice 25 and a plurality of orifices 26 suitably spaced in a plurality of circles lying within the plane of baffle 19 and concentrically spaced from central orifice 25. Orifices 25 and 26 are each circumscribed by annular extrusions 27 which extend substantially perpendicular to forwardly disposed surface 28 of baffle 19.

Baffle 18 is like baffle 16 and is formed to the general circular configuration of Fig. 2 having an outside diameter after forming substantially equal to the inside diameter of body 11, having a forwardly disposed face 38, a centrally disposed orifice 35 with a minimum diameter greater than that of orifices 25 and 26 of baffle 19 and having a plurality of orifices 36 equal in diameter with orifice 35 and spaced concentrically about said orifice 35. Orifices 36 are fewer in number than are orifices 26 of baffle 19 and orifices 35 and 36 are each circumscribed by an annular extruded portion 37 of baffle 18 formed to a cross-sectional configuration similar to that shown at 27 in Fig. 5 and projecting forwardly from and substantially perpendicularly to the forward face 38 (Fig. 2). Baffle 18 is further formed with a rearwardly extending

flange 33 similar to the flange 23 of baffle 19 shown in detail in Fig. 5.

Baffle 17 is formed to the general circular configuration shown in Fig. 3 having an outside diameter after forming substantially equal to the inside diameter of body 11. Baffle 17 has a single centrally disposed orifice 45 with a diameter substantially equal to the inside diameter of inlet tube 14 (Fig. 1). Orifice 45 is further formed with a forwardly projecting extruded peripheral portion 47 circumscribed about said orifice and formed substantially to the cross-sectional configuration shown at 27 in Fig. 5. Baffle 17 also has a rearwardly projecting annular flange 43 (Fig. 3) formed substantially as shown at 23 in Fig. 5.

Baffle 16 is formed to substantially the same general configuration shown as baffle 18 shown in detail in Fig. 2 and described before herein.

Each of said baffles 16, 17, 18 and 19 (Fig. 1) are arranged within body 11 perpendicular to the longitudinal axis of body 11 so as to form successive chambers 51, 52, 53, 54 and 55 within the assembled muffler 10. Said baffles 16, 17, 18 and 19 are spaced from each other and from outlet end cap 13 by respective linear distances required to define an approximate volumetric relationship between chamber 52, and chambers 53, 54, 55 and 51.

Tests have indicated that baffle 16 should be spaced from baffle 17 a distance not less than one and one-half inches and not greater than two and one-half inches as measured along the longitudinal axis of body 11. Baffle 18 is spaced from baffle 17 sufficiently far to define a chamber 53 having a volume approximately two and one-half times that of chamber 52 formed by the spaced relationship just described between baffles 16 and 17. Baffle 19 is spaced from baffle 18 sufficiently far to define a chamber 54 having a volume approximately one and one-half times that of chamber 52. All baffles 16, 17, 18 and 19, mutually interspaced as just described, are spaced from outlet cap 13 a sufficient distance to form chamber 55 having a volume not greater than twice the volume of chamber 52. Cylindrical body 11 and intake end cap 12 previously described in part have sufficient inside dimensions to define a chamber 51 having a volume not less than two times the volume of chamber 52.

Operation

In operation the exhaust pipe 20 (Fig. 1) of an engine is secured in gas-tight engagement within inlet tube 14 by suitable means such as for instance clamp 39 and outlet tube 15 is secured by similar means 49 in engagement within a suitable tailpipe 30.

Exhaust gases from the engine (not shown) are introduced under engine pressure and at normal engine exhaust temperature through engine exhaust pipe 20 into chamber 51 where said gases are cooled by conduction as they come in contact with the walls of chamber 51. Said gases are then urged under engine pressure through orifices 66 of baffle 16 and into chamber 52. In passing the gases through the moderately sized orifices of baffle 16 the exhaust noise components having intermediate frequency characteristics are modulated to sound waves of less undesirable frequencies. From chamber 52 said exhaust gases are passed substantially under engine pressure through orifice 45 of baffle 17 whereby objectionable high frequency components of exhaust noise are modulated to sound waves of a less objectionable frequency. From chamber 53 the gases are passed through orifices 36 for a second sound modulating effect similar to that produced by orifices 66 of baffle 16 which are similar in size, number and configuration to orifices 36. From orifices 36 the gases pass into chamber 54 and then pass through orifices 26 where the exhaust noise components of lower objectionable frequencies are modulated to frequencies which are less

objectionable in character. Thereafter all exhaust gases are ejected through outlet opening 22, outlet tube 15 and tailpipe 30.

The normal resistance to the flow of a fluid through an orifice in a plane surface is reduced and the rate of flow of exhaust through baffle orifices 66, 45, 36 and 26 is increased over the normal rate by means of the extruded configuration of each baffle orifice which is employed in the device as shown in the cross-sectional view of orifices 25 and 26 in Fig. 5. The increase in rate of flow through each baffle orifice which is thus achieved serves to reduce the total back pressure imposed by muffler 10 upon the engine.

By arranging successive baffles in the sequence shown in Fig. 1 straight line passage of exhaust gases through the muffler is prevented, except for a limited proportion of the total volume of the total gas which is permitted to pass directly along the longitudinal axis of muffler 10 as a further aid in reducing the back pressure of the muffler and is subjected to the successive sound modulating effect of central orifices 65, 45, 35 and 25 substantially as previously described.

The previously described peripheral extruded portions of all baffle orifices such as that shown at 27 in Fig. 5 further serves to expose more total heat conducting surface to contact with the exhaust gases and therefore serve the additional purpose of providing increased cooling facilities for the gases as a further aid in diminishing the sound level of the exhaust gases.

In the baffles shown and described, baffle 16 has seven orifices, baffle 17 has a single orifice as previously described, baffle 18 has seven orifices and baffle 19 has nineteen orifices. In mufflers of larger diameter baffles corresponding to baffles 16, 18 and 19 may have a greater number of orifices. For instance in one muffler having a greater diameter, the baffle corresponding to baffle 16 as illustrated has nineteen orifices; the baffle corresponding to 17 has one orifice; the baffle corresponding to 18 has nineteen orifices; and the baffle corresponding to baffle 19 has thirty-three orifices.

In sound tests conducted with a muffler constructed substantially according to the embodiment of my muffler illustrated in Figs. 1-5, inclusive, and described herein, as compared to a muffler of conventional design, both 45 mufflers being employed with a conventional truck engine operating at full throttle, the following results were observed and measured by means of a conventional sound level meter and octave band noise analyzer:

Source of Sound	Noise Level in Decibels	Noise Analysis in Sones
Engine running at full throttle with:		
(1) No muffler	100	165
(2) Conventional type muffler	91	107
(3) Improved muffler described herein	89	95

Engine back pressure tests indicated that the effective back pressure on an engine equipped with the muffler described herein was approximately one-half inch of mercury when the engine was operating at full throttle R.P.M. and under normal load conditions. Comparable tests in which a muffler of conventional design was similarly employed indicate that such mufflers exert back pressures in the order of two inches of mercury under similar conditions.

Baffles 16, 17, 18 and 19 are secured within body 11 by welding as seen at weld 71 in Fig. 5 although any other suitable heat-conducting means may be employed such as for instance brazing, soldering, riveting, or tight frictional engagement which may be achieved by methods well known in the art. I prefer to insure satisfactory heat conduction by welding.

The muffler configuration which I have described herein and illustrated in the appended drawings is particularly suited to production methods whereby a protective coat-

ing such as a coating of metallic or ceramic materials is applied to all interior and exterior surfaces of a muffler after the muffler is assembled. The unidirectional alignment of all protruding surfaces of baffles 16, 17, 18 and 19, together with the concave inner configuration of end cap 13 serve to facilitate the rapid drainage of coating material from the interior of the muffler which is essential to such production methods.

It is to be understood that the above described embodiment of my invention is for the purpose of illustration only and various changes may be made therein without departing from the spirit and scope of my invention.

I claim:

A muffler comprising a hollow casing having an inlet end and an outlet end; a substantially hemispherical inlet head having an inlet tube at the inlet end; a substantially hemispherical outlet head having an outlet tube at the outlet end; a first transverse baffle secured within said casing adjacent to the inlet end and having a plurality of extruded orifices consisting of a centrally positioned orifice extending therethrough and a plurality of other orifices arranged concentrically with said centrally positioned orifice and extending therethrough, all of said orifices being formed with circular flanges; a second transverse baffle having a single extruded orifice extending therethrough and formed with a circular flange and spaced from the first baffle by a distance of from one and a half inches to two and one half inches measured along the longitudinal axis of the body for defining a first chamber of predetermined volume intermediate said baffles; a third transverse baffle substantially similar in configuration

10

15

20

25

with said first baffle and spaced from said second baffle a sufficient distance to define a second chamber intermediate said second and third baffles, having a volume approximately two and one-half times the volume of said first chamber; a fourth transverse baffle having a plurality of extruded orifices, greater in number than said first baffle, interpositioned between said third baffle and said outlet head for forming a third chamber intermediate said third and fourth baffles having a volume approximately one and one-half times the volume of said first chamber, and for further forming a fourth chamber intermediate said fourth baffle and said outlet head having a volume not greater than twice the volume of said first chamber; all of said baffles being further spaced from said inlet head a distance sufficient for defining an intake chamber intermediate said inlet head and said first baffle having a volume not less than twice the volume of said first chamber.
